[57] CLAIM

The ornamental design for a fire hose wringer, as shown and described.

DESCRIPTION

FIG. 1 is a perspective view of a fire hose wringer, showing my new design;

FIG. 2 is an elevational view of the latch side thereof;

FIG. 3 is an elevational view of the hinge side thereof;

FIG. 4 is a rear elevation thereof;

FIG. 5 is a front elevation thereof;

FIG. 6 is a top plan view thereof;

FIG. 7 is a bottom plan view thereof; and,

FIG. 8 is a perspective view thereof similar to FIG. 1 but with the top roll frame unlatched and in open position to receive or release fire hose with large couplers.
